UNITED STATES PATENT OFFICE.

FREDERICK HACHMANN, OF ST. PAUL, MINNESOTA, ASSIGNOR TO
BRAINERD S. GRIFFIN, OF ST. PAUL, MINNESOTA.

GRAIN-DOOR FOR CARS.

SPECIFICATION forming part of Letters Patent No. 783,633, dated February 28, 1905.

Application filed December 21, 1903. Serial No. 185,940.

To all whom it may concern:

Be it known that I, FREDERICK HACHMANN, a citizen of the United States, residing at St. Paul, in the county of Ramsey and State of Minnesota, have invented certain new and useful Improvements in Grain-Doors for Cars; and I do hereby declare the following to be a full, clear, and exact description of the invention, such as will enable others skilled in the art to which it appertains to make and use the same.

My present invention has for its object to provide a simple, cheap, strong, and durable grain-door for railway-cars which is capable of quick and easy manipulation and which in all ways is efficient for the purposes had in view.

To the above ends the invention consists of the novel devices and combinations of devices hereinafter described, and defined in the claims.

The invention is illustrated in the accompanying drawings, wherein like characters indicate like parts throughout the several views.

Figure 1 is a view in side elevation, showing the central portion of a box-car and showing one of my improved grain-doors applied thereto in working position. Fig. 2 is a transverse vertical section taken approximately on the line $x^2 x^2$ of Fig. 1. Fig. 3 is a longitudinal vertical section on the line $x^3 x^3$ of Fig. 2; and Fig. 4 is a view corresponding to Fig. 2, but with the grain-door shown in an elevated position by full lines and in a slightly-raised but operative position by dotted lines.

The numeral 1 indicates the body of the freight-car, and the numeral 2 one of the side-door openings thereof.

The numeral 3 indicates the main or lower section, and the numeral 4 the upper or supplemental section, of the grain-door, which door-sections, respectively, have hinge members 5 and 6. The hinge members 5 and 6 are pivotally connected, and those near the edges of the door are also pivotally connected to the lugs 7 of a pair of sliding blocks 8. These sliding blocks 8 are mounted to slide vertically on supporting bars or rods 9, which bars, as shown, are constructed of flat iron strips

and are pivotally supported at their upper ends from the overhead beam of the door-frame, being preferably rigidly secured to a transverse pipe or rod 10, which in turn is pivotally mounted in bearing-brackets 11 on the said overhead beam. Also, preferably, but not necessarily, the lower ends of these bars are rigidly tied together by a transverse pipe or rod 12. The sliding blocks 8 are provided with heavy hand-screws 13, by means of which they may be rigidly secured in any desired vertical adjustment on the depending bars or hangers 9. The ends of the grain-door sections overlap with the sides of the door-frame, as best shown in Fig. 3, to prevent them from being forced outward through the doorway under the pressure of the grain from within. On the floor of the car at the doorway are slightly-raised retaining-lugs 14, which hold the lower portions of the grain-door when in its lowermost position close against the door-frame. To prevent the supplemental door-section 4 from being forced inward when the grain-door is in its lowermost closed position, (indicated in Figs. 2 and 3,) retaining-hooks 15 are pivoted to the sides of the door-frame in position for engagement with the upper edge of the said door-section 4, as shown in Figs. 2 and 3.

To support the grain-door in an elevated inoperative position close to the top of the car, as shown by full lines in Fig. 4, suspending-hooks 16 are pivoted to the transverse roof-beams of the car-body. These suspending-hooks 16 in their preferred construction engage with the transverse tie-rod 12, which unites the free ends of the swinging bars or hangers 9.

For most purposes the grain-door must have such height that if made in a single section the two doors on the opposite sides of the car when swung upward to the roof of the car would overlap with each other, and hence the advisability or necessity of the supplemental hinged door-sections. With the door constructed as described when it is desired to throw the same upward into an inoperative position (illustrated by full lines in Fig. 4) the sliding blocks 8 are dropped to the lower ends

of the swinging hangers 9, the main door-section 3 is turned on its hinge upward against the supplemental section 4 and in line with the hangers 9, and then the whole folded door, 5 including the hangers, is swung pivotally inward and upward into the said inoperative position and is there secured by the hooks 16, as already described. The above operation is a very simple one and may be very easily and 10 quickly accomplished, since all the parts are thrown into the positions noted by swinging or pivotal movements, no direct sliding lift being necessary.

In unloading coal, grain, or some other materials it is desirable that the grain-door be supported in a slightly-raised position, so as to leave an opening only at the bottom of the door—as shown, for instance, by dotted lines in Fig. 4. As is evident, the grain-door supported as above described may be very quickly and easily set in this adjustment simply by forcing it upward and forcing sliding blocks 8 upward on the hangers 9. As is also evident, the grain-door may be supported in 25 any desired operative vertical position by tightening the screws 13 onto the hangers 9, and thereby locking the blocks 8 thereto. If for any reason a grain-door when thus raised, or at any other time, for that matter, extends 30 higher than is necessary or desirable, the supplemental section 4 may be turned inward and downward against the main section 3.

As is evident, the device above described is capable of modification within the scope of 35 my invention as herein set forth and claimed. For instance, the door-hangers or "suspension-bars," so called, might be round in cross-section instead of being flat and might be pivotally connected both to the car and to the 40 grain-door in a great many different ways.

However, the construction described has its important advantages and involves patentable features even in its details.

What I claim, and desire to secure by Letters Patent of the United States, is as follows: 45

1. The combination with a car-body, having a door-opening, of a grain-door coöperating with said door-opening; a pair of hangers pivoted to the upper portion of the car-body, a pair of blocks or brackets slidable on the 50 free portions of said hangers and to which said grain-door is pivotally attached for folding movements, substantially as described.

2. The combination with a car-body having a door-opening, of a grain-door made up of 55 pivotally-connected sections, a pair of hangers pivoted to the upper portion of the car-body, and a pair of sliding blocks or brackets working on said hangers and to which both sections of said grain-door are pivotally attached 60 by axially-alined hinges, substantially as described.

3. The combination with a car-body having a door-opening, of a grain-door made up of 65 the hinged sections 3 and 4, the pair of hangers 9 pivotally supported on the upper portion of the car-body by a transverse rod 10, and tied at their lower ends by a rod 12, and the blocks 8 slidable on said hangers 9, provided with projecting lugs 7 connected with the hinges 70 of said grain-door, said blocks further having set-screws 13 for securing them on said hangers in any desired vertical adjustment, substantially as described.

In testimony whereof I affix my signature in 75 presence of two witnessess.

FREDERICK HACHMANN.
